Continuation of application Serial No. 658,055,
March 29, 1946. This application August 13,
1949, Serial No. 110,167

5 Claims. (Cl. 230—122)

1

This application is a continuation of application Serial No. 658,055, filed March 29, 1946, now abandoned, and relates to rotary power conversion machines including axial-flow compressors, turbines, pumps, and the like. More specifically, the invention involves improving the efficiency of such machines by more efficient and increased energy interchange between the machines and the compressible fluid passing through the machines.

For axial-flow compressors, larger quantities of energy may be added to the gas being compressed if appropriate types of flow are maintained in various stages of the compressor. It has been previously known that some other flow than vortex flow might be desirable, because energy cannot be added efficiently to a fluid having vortex flow, or in other words, energy cannot be added in as great a quantity per stage with given Mach number and maximum lift coefficient as when the flow is other than vortex flow. This can be easily demonstrated by the drawing of velocity diagrams, which for vortex flow will not be symmetrical and will consequently indicate that energy cannot be added efficiently. In spite of this knowledge little progress has been made toward the attainment of improved efficiency through proper flow, and this may have been due to the erroneous assumption that a fixed inlet grid or blade stage for an axial compressor would provide solid flow with uniform axial velocity or a flow with uniform axial velocity substantially different from vortex flow.

That a stationary initial stage will produce only vortex flow with constant axial velocity can be demonstrated as follows:

The condition of equilibrium in a fluid having velocity components in the axial and tangential directions only is expressed by the following equations:

$$\frac{\partial H}{\partial r} = V_a \frac{\partial V_a}{\partial r} + V_t \frac{\partial V_t}{\partial r} + \frac{V_t^2}{r}$$

where

H = energy

V_a = axial velocity

V_t = tangential velocity

r = radius

With the axial velocity constant, as is the case with straight flow of fluid into the fixed inlet stage, and with the energy remaining constant with radii, since the uniform energy distribution of straight flow into the fixed inlet stage cannot be changed by the fixed inlet stage, the above equation becomes:

$$\frac{\partial V_t}{\partial r} + \frac{V_t^2}{r} = 0$$

This is satisfied only by $V_t r = \text{constant}$ which is definition of vortex flow.

2

By my invention I recognize this fact and so take care to transform the vortex flow due to the fixed inlet to another type of flow to which energy may be efficiently added. I provide for the sufficient addition of energy to the gas being compressed while it has the appropriate type of flow and then transform the flow to vortex and finally to axial. For turbines operating on compressible fluid I arrange for a similar procedure. The fluid is transformed from axial flow to vortex flow and then to a flow from which energy may be efficiently abstracted. Then the fluid is reconverted to vortex flow and to axial flow.

By my invention I have provided appropriate stationary and rotary blade stages in turbines and compressors that will make definite provision for the appropriate conversion of the flow of the fluid as outlined above.

An object of the present invention is to provide improvements in rotary power conversion machines such as axial-flow compressors and turbines operating on or by compressible fluids, the improvements involving the appropriate arrangement of blade stages required for efficient energy transfer with respect to the machines. My machines provide for the successive transformation of the flow of fluids passing therethrough from axial to vortex to a form that may be approximately solid flow, with respect to which the energy transfer is carried out; then back to vortex and axial, in which condition the fluid leaves the machines.

Another object of the invention is to improve a rotary power conversion machine in such a way as to insure with certainty that the fluid passing through the machine is converted to the proper approximation of solid flow, in which condition the energy transfer with respect to the fluid is to be made. I have discovered that this approximation of solid flow is solid flow minus a vortex flow and should have a variable axial velocity.

Other objects will appear from the disclosure.

In the drawings:

Fig. 1 is a diagrammatic partial view in section 45 of a compressor of the present invention;

Fig. 2 is a view showing tangential velocity diagrams for various regions of the compressor of Fig. 1;

Fig. 3 is a view showing axial velocity diagrams 50 for various regions of the compressor;

Fig. 4 is a view showing energy diagrams for various regions of the compressor;

Fig. 5 is a more detailed physical showing of a compressor of the present invention;

Fig. 6 is illustrative of the velocity diagrams along certain specified sections of the blading of the compressor of Fig. 5;

Fig. 7 shows certain velocity vectors of the diagrams of Fig. 6 in superimposed relation; and

Fig. 8 is illustrative of the velocity diagrams

along other specified sections of the blading of the compressor of Fig. 5.

In Fig. 1 is shown a compressor of the axial flow type, designated by the reference character 10. The compressor comprises a stator 11 and a rotor 12, having an axis of rotation beneath the portion of the rotor shown, as viewed in Fig. 1. The stator 11 has a blade stage 13 forming an inlet for gas or compressible fluid to be compressed by the compressor 10, flowing from left to right therethrough, as viewed in Fig. 1. To the right of the stationary blade stage 13 is a rotary blade stage 14 carried by the rotor 12 and a stationary blade stage 15 carried by the stator 11. The stages 14 and 15 constitute an inducer. To the right of stage 15 are a rotary blade stage 16 carried by the rotor 12 and a stationary blade stage 17 carried by the stator 11. The stages 16 and 17 constitute the compressor proper of the axial compressor 10. To the right of the stage 17 are a rotary blade stage 18 carried by the rotor 12 and a stationary blade stage 19 carried by the stator 11, which stages constitute an educer. To the right of the stage 19 is a stationary blade stage 20, which constitutes an outlet for the compressed fluid from the compressor.

Each of Figs. 2, 3, and 4 constitutes a set of diagrams representing successive conditions of the flow of compressible fluid through the compressor 10. Each diagram represents a condition of velocity or energy at exit of the flow from the stage below the right side of which the diagram is positioned and is designated with the reference character of the particular blade stage with *a*, *b*, or *c* added, depending upon whether the diagram is of tangential velocity, axial velocity, or energy. Exceptions are made of the diagrams at the extreme left, which are designated by 10^a, 10^b, and 10^c and represent conditions of velocity and energy upon entrance of the compressible fluid to the first stationary stage. Each diagram by its lateral dimension represents a relative quantity of velocity or energy. The relative quantity of velocity or energy is represented for the various points from stator blade tip to stator blade root and from rotor blade tip to rotor blade root by the lateral dimensions of the diagrams at the corresponding points thereon from bottom to top.

Consider Diagrams 10^a, 10^b, and 10^c. The fluid or gas entering the compressor 10 will normally have axial or straight flow, which is characterized by zero tangential or rotational velocity, uniform axial velocity, and uniform energy. Diagram 10^a by being a single vertical line represents zero tangential velocity. Diagrams 10^b and 10^c by being rectangles or having uniform width from bottom to top represent uniform axial velocity and uniform energy.

The fluid or gas enters the stationary blade stage 13 and the blades thereof are angled and shaped so as to cause the fluid to have a rotative or tangential velocity. Since the stage is stationary, the rotating flow necessarily becomes a vortex flow, which as shown by the Diagrams 13^a, 13^b, and 13^c involve uniform energy, uniform axial velocity, and tangential velocity inversely proportional to radius. This tangential velocity may be described as decreasingly variable when considered in an outward direction from the center of rotation. Hereafter when a velocity or energy is described as being increasingly or decreasingly variable, it will be understood that the velocity or energy is being considered at successive points of the blade stage in question at

increasingly greater distances from the center of rotation.

Since, as can be demonstrated, energy cannot be added efficiently or in large quantity to vortex flow with its decreasingly variable tangential velocity and uniform energy, it is necessary to adjust appropriately these quantities. This is accomplished by rotary blade stage 14 and stationary blade stage 15 constituting an inducer. The blades of the rotary stage 14 are so shaped and disposed as to alter the vortex flow received from the stationary stage 13 to another flow having an increasingly variable energy, as shown by Diagram 14^c, which is characterized of a desired approximation of solid flow, namely, solid flow minus vortex flow. Solid flow is flow characterized by tangential flow proportional to radius or distance from the axes of rotation. It is to be noted that the flow coming from rotary stage 14 is not solid flow, since, as shown by Diagram 14^a, the tangential velocity is still slightly inversely proportioned to radius, and the energy distribution has been suitably modified; the energy has been changed from uniform to increasingly variable. Some energy has been added, as is evident from a comparison of Diagrams 13^c and 14^c, but only to the extent required for adjustment of the energy distribution as aforesaid. It is to be noted that the axial velocity has been transformed by the rotating stage 14 to slightly increasingly variable.

The blades of stationary stage 15 are so shaped as to transform the flow coming from rotary stage 14, which was stated to have the increasingly variable energy distribution of solid flow minus vortex flow, to solid flow minus vortex flow. This involves, as shown by the tangential velocity Diagram 15^a, making the tangential velocity directly proportional to radius with a correction in an amount equal to minus vortex flow. The solid flow minus vortex flow coming from stationary blade stage 15 is also characterized by an increasingly variable axial velocity, which has an average equal to the uniform axial velocity that would be characteristic of the aforesaid solid flow.

To summarize the function of the stages 14 and 15: these stages have converted the vortex flow resulting from the initial stationary stage 13 to solid flow minus vortex flow having increasingly variable axial velocity, which is the appropriate condition of the compressible fluid or gas for the addition of energy in significant quantity.

The compressible fluid or gas is now acted upon by the rotating blade stage 16. The blades of this stage are so shaped and disposed as to add energy in significant quantity as is to be seen from a comparison of energy Diagrams 15^c and 16^c. The energy distribution remains the same, or in other words the energy of the flow leaving rotary stage 16 is increasingly variable. The rotary stage 16 will necessarily have a vortex effect upon the flow and will add vortex flow to the extent of changing the flow from solid flow minus vortex flow to solid flow plus vortex flow. This can be seen from a comparison of tangential velocity Diagrams 15^a and 16^a. The tangential velocity in Diagram 16^a is represented as less increasingly variable than that of Diagram 15^a. The axial velocity has become decreasingly variable as shown in Diagram 16^b. These changes in tangential velocity and axial velocity produced as incidents of the increase in energy effected by rotary blade stage 16 demonstrate the need for the flow reaching rotary stage 16 to be solid flow

minus vortex flow and to have increasingly variable axial velocity. Otherwise the vortex flow effect of the rotary stage 16 would cause the tangential velocity to be even less increasingly variable than shown by Diagram 16^a and perhaps decreasingly variable and the axial velocity to be more decreasingly variable than shown by Diagram 16^b. Under these conditions the addition of energy would be inefficient and small.

The flow passes now to the stationary stage 17, of which the blades are so shaped and disposed as to return the flow to approximately its condition upon entry to rotary stage 16 insofar as tangential and axial velocities are concerned. The flow coming from stationary stage 17 is solid flow minus vortex flow and has increasingly variable tangential and axial velocities, as shown, by Diagrams 17^a and 17^b. The energy continues to be increasingly variable, as shown in Diagram 17^c, for a stationary stage cannot change energy distribution.

The rotary and stationary blade stages 16 and 17 comprise the compressor proper of the machine, because they cooperate to add energy and to preserve the condition of the flow. Only one set of rotary and stationary compressor blade stages has been shown for the theoretical considerations of Figure 1 since the action of one or several of these sets may if preferable be adequately demonstrated by the description and showing of only one set for the time being; however, it is to be understood as is to be subsequently demonstrated that as many sets may be employed as may be necessary or desirable for sufficient addition of energy.

The flow now passes to the rotary stage 18 having blades shaped and arranged to alter the energy distribution of the flow to an energy distribution of vortex flow, to which condition the compressible fluid or gas is later to be transformed. Vortex flow has uniform energy, and the blades of rotary stage 18 accomplish the change from increasingly variable energy of Diagram 17^c to the uniform energy of Diagram 18^c. This change in energy distribution may be made with or without the addition of energy. It will be noted from velocity Diagrams 18^a and 18^b that the tangential and axial velocities have become less increasingly variable through the action of rotary stage 18.

The flow now passes to the stationary stage 19, having blades shaped and arranged to change the flow further so that it not only has the uniform energy distribution of vortex flow but is vortex flow itself. The energy is uniform, as indicated by Diagram 19^c; the axial velocity is uniform; and the tangential velocity is decreasingly variable.

The rotary and stationary stages 18 and 19 are to be considered an educer, since they transform the approximate solid flow resulting from the compressor, namely, solid flow minus vortex flow, to vortex flow, from which condition the change to straight or axial flow by the stationary outlet blade stage 20 can be made. The change to vortex flow must be made, because otherwise the change to straight flow cannot be completely made. The return to straight flow is demonstrated by the Diagrams 20^a, 20^b, and 20^c, which show that it is accompanied by zero tangential or rotative velocity, and uniform energy. A comparison of energy Diagrams 20^c and 10^c shows the amount of energy added to the compressible fluid or gas by the axial-flow compressor, which will

be represented mainly by increase in pressure if the axial velocity is not appreciably changed.

In the more detailed physical showing of a compressor appearing in Figure 5, paired sets of rotor and stator blading running for convenience to the number of eight, are to be noted incorporated in the main working compressor portion proper 21 of the compressor. Compressor 10, of which the embodiment shown corresponds generally such as regards like reference numerals, with compressor 10 shown in Figure 1, comprises a stator component 11 and a rotor component 12. For the mean working compressor portion 21, there may be provided an intake having preliminary staging therein comprising an inlet grid having stator blades 13 and an educer having respective rotor blades 14 and stator blades 15. As previously noted, it is the purpose of the grid 13 to transform the axially flowing compressor fluid into a state of vortex flow while the inducer elements 14 and 15 serve to prepare the fluid into an appropriate state for introduction into the working compressor portion of the machine 10. For the delivery end of the working compressor portion of which the last set of blades shown is formed on a stator element 87, there may be provided an outlet comprising final discharge or outlet means 20 and an interposed educer comprising respectively, a rotor element 18 and a stator element 19. As set forth hereinabove, it is the purpose of the educer to transform the fluid delivered by the working compressor portion into a state of vortex flow suitable for introduction into the outlet means for restoration to straight axial flow. Appearing directly over the axis of the compressor 10 of Figure 5 are cross sections showing the blade profiles such as may be appropriately used. Since any one of a number of combinations of blade profiles may be used to operate according to the theory of the present invention, the form of blade actually selected is purely for purposes of illustration. For instance, the angle of attack of the blade entrance with respect to the relative flow and the angle of effective turn or lift may be taken from published behavior curves of diverse blade profiles well known to the art, for instance, the N. A. C. A. publication 2409, for which see National Advisory Committee for Aeronautics Report No. 460.

In Figure 6 is shown an enlarged view of the blade sections just described in connection with the machine of Figure 5. Between the respective sets of blading have been interposed fluid velocity diagrams to serve as an aid in understanding the machine characteristic operation sought for. The blade sections selected happen to be radially successive for convenience sake; that is to say, there appear respectively a root section, a mean intermediate section, and a tip section for a blade of each rotor or stator element of the machine shown. Thus inlet grid 13 of Figure 6 corresponds with the inlet grid 13 of Figure 5. The educer rotor 14 and educer stator 15 of Figure 5 correspond with the blade sections respectively shown at 14 and 15 in Figure 6. In the embodiment of Figure 6 selected to be illustrative, the axial flow of entering fluid has been given an assumed velocity of 400 units. Accordingly at the root section of inlet grid 13, at the mean intermediate section of grid 13, and at the tip section of grid 13, the straight flow vector 400 will be observed to be directed toward the blading at zero inclination. It is the purpose of the fixed inlet grid to transform the straight flow such as characterizes the incoming working fluid into

vortex flow. Hence, the inlet portions of the blades 13 are provided with leading edges having a zero angle of attack to the incoming working fluid. The discharge portions of the blades 13 of the inlet grid are provided with trailing edges of which the discharge angles vary in conformity with the flow of fluid for providing vortex flow such as is characterized by a rotational angular velocity varying decreasingly outward. In other words, the vortex flow at the root section has a relatively higher angular rotational velocity than the mean intermediate section and at the tip section a relatively lower rotational angular velocity. In vector Diagram 13^d the angular rotational velocity is shown to be 463 units whereas at the mean intermediate section and the tip section respectively at 13^e and 13^f, the angular rotational velocities diminish to 377 and 323. The blade shapes and proportions may be taken as convenient from an N. A. C. A. publication in order to produce the desired result stated. Such publications also include the blade lift setting in order to bring about the proper change in direction of flow for a specified blade proportion. Inasmuch as the axial component and the angular rotational component of the absolute velocity of the fluid discharged from grid 13 is known, the absolute velocity of the fluid discharged may be determined and represented by a vector. The flow is delivered as represented by this vector into the rotor element of an inducer provided for the compressor of the instant invention, of which the rotor element is designated 14, and the stator element designated 15.

At the respective root, mean intermediate, and tip sections of rotor element 14 the blade velocity, varying outward with radius, is represented as of the order respectively of 700 units, 864 units, and 1003 units in Figure 6. The addition of this blade velocity vectorwise to the vector representing the flow of fluid from inlet grid 13 will yield a resultant vector shown in Figure 13^d at 102, in Figure 13^e at 104, and in Figure 13^f at 106. These resulting vectors are representative of the relative flow of fluid incoming to inducer rotor element 14. It will be seen that the inlet portions of the blade sections of rotor 14 are provided with leading edges presenting a substantially zero angle of attack to the respective velocities represented by vectors 102, 104, and 106. The radially successive sections of the rotor blade 14 may be noted to have an angle of lift increasing outwardly. That is to say, the zero lift line 103 of the basic section adjacent the rotor element in Diagram 13^d at the root of the blade lies substantially parallel with the fluid flow discharge lines. The difference between the inlet and discharge angle at the root section of blade 14 will be seen to comprise an angle X_{14} of minor consequence. The difference between the inlet and discharge angles of fluid for the mean intermediate section of blade 14 is of the relatively larger quantity Y_{14} in Diagram 14^e, and the difference between the entrance to discharge velocities at the tip section Diagram 14^f of blade 14 amounts to a still larger angle Z_{14} . Vectorially computable from the relative discharge velocity from blade 14 and the blade velocity, is the absolute discharge velocity of the fluid leaving blade 14 shown to be of the value of 585 in Diagram 14^d, 620 in Diagram 14^e, and 660 in Diagram 14^f. These increasingly variable absolute velocities just noted yield a tangential component which will conform substantially to a mean value at all radii, namely, the angular rotational

velocity 478 at the root in Diagram 14^d, 472 at the intermediate section according to Diagram 14^e, and 467 at the tip section in accordance with Diagram 14^f.

5 The inducer stator blading in Figure 6 next in succession comprises a blade 15 of which the inlet portion presents a leading edge having a substantially zero angle of attack to the oncoming fluid. The basic tip section of blade 15 will be 10 seen to have a zero lift line 107 lying in Diagram 15^f in substantial parallelism with the normal or natural flow of fluid introduced into the inducer stator element, thus making for a relatively inconsequential change in direction denoted by 15 angle Z_{15} of Figure 15^f of the inlet to discharge velocities. The change of inlet and discharge velocities, or as ordinarily stated, the angle of lift of blade 15 is of a greater order of value Y_{15} at the mean intermediate section, as shown in Figure 15^e and at the root section of angle of lift 20 attains a value of X_{15} , which is even greater as shown at Figure 15^d than the angle of lift at Figure 15^e. Blade 15 hence has an angle of lift varying inversely with radius as is contrasted with 25 blade 14 which angle of lift varies with radius. This decreasing characteristic of variation in inlet and discharge angle with respect to radius in blade 15 has a decided effect on the discharge velocities from the discharge portions of blade 15. The 30 discharge velocities shown in Diagrams 15^d, 15^e, and 15^f to be of the value 418, 510, and 595 vary increasingly outward and with appropriate clockwise change in direction such that the absolute angular rotational velocity of the radially successive sections outward have the increasingly variable characteristic substantially of solid flow. The absolute angular rotational velocity in Diagram 15^d will be seen to be 215, while at the mean 35 intermediate section shown by Diagram 15^e the absolute angular rotational velocity is of the value 315, and at the tip section as diagrammed at 15^f the absolute angular rotational velocity is of value 398. In this flow condition of modified solid flow the motive fluid may suitably be introduced into the working compressor means.

45 The first element of the working compressor means of Figure 6 is shown to be a rotor 16 of which the root section has a blade speed of 700, the mean intermediate section has a blade speed of 852, and the tip section has a blade speed of 987. A vectorial addition as in Diagrams 15^d, 15^e, and 15^f of the absolute fluid discharge velocity and the absolute blade velocity will yield a 50 vector as at 108, 110, and 112, which illustrates the relative flow of incoming fluid as respects the working compressor rotor 16. In the state of flow in which the fluid is delivered to the working compressor means, energy may be added in 55 relatively great amounts for each successive stage of the compressor traversed at a relatively high degree of efficiency. The working compressor serves to increase the pressure on the fluid passing therethrough and at the same time preserves that characteristic in flow received 60 from the inducer means of outwardly increasing angular rotational velocity and absolute velocity, that is, the velocities 418 and 215 of Diagram 15^d, 510 and 315 of Diagram 15^e, and 595 and 398 of Diagram 15^f or approximations of those values. It has been found that upon reception of a fluid in the state at which the inducer delivered it, the working compressor means can operate to 65 full advantage if it is designed to operate along the lines of symmetrical flow diagram principles. 70 For one thing, the pressure rise in each stator or 75

rotor element is the same according to a symmetrical flow diagram regardless of whether in stator or rotor. The change in direction of flow of the fluid passing through each set of blades is also of the same size angularity even if of opposite algebraic sign as compares the stator and rotor element. By way of amplifying on the subject of symmetrical flow diagrams, it might be said that the symmetrical flow desirably takes place at the mean intermediate section of the blade with proper accommodations being provided for at the tip and root sections by readily done compensations in the appropriate velocity diagrams. The mean intermediate section of blade 16 will be seen to yield such a velocity diagram as at 16°. The angle of lift Y_{16} in 16° serves as a measure of the change of angularity of the fluid in passing through the mean intermediate section of blade 16.

In Figure 7 the velocity vector Diagram 16° of Figure 6 has been reproduced in part and there-over in Figure 7 has been superimposed the entrance velocity EV_{Rel} , relative to the mean intermediate section of blade 16 as shown in velocity Diagram 15°. The change of entrance to discharge angle measured by angle Y_{16} of Diagram 16° likewise appears in Figure 7. The change of vectors wrought by the angle change Y_{16} is represented by the value Δcu_{Rel} . Additionally superimposed in Figure 7 is the absolute discharge velocity DV_{Abs} from the working compressor first stator element 17. In the velocity Diagram 17° of the mean intermediate section of blade 17, appears the change of entrance to discharge angle Y_{17} which will also be found among the superimposed diagrams of Figure 7. The vector change wrought by this change of angle will be seen in Figure 7 to amount to the vector difference Δcu_{Abs} . Inasmuch as the axial component of the fluid flow in the working compressor blading 16 and 17 is substantially constant through the mean intermediate section, the resulting right triangles are in essentials symmetrical with respect to the axis of the machine. The change in relative flow of fluid to and from the rotor element 16 is substantially the same as the change of absolute velocity respecting direction of flow to and from the stator element 17. Inasmuch as the quantity s along the base of the resulting triangle approximates the quantity t along the base of the triangle, a diagram results in Figure 7 which is substantially symmetrical about the axial velocity flow component 400 and axis of the machine. As stated, since the change in direction of the angles of flow of the fluid in going through each set of working compressor blading, regardless of the identity of the blading being rotor or stator, is substantially the same, a pressure rise may be achieved between each successive set of blading which is also substantially the same. By way of return to Figure 6 it is to be noted in the vector Diagrams 17^d, 17^e, and 17^f that the absolute velocities are still preserved in proportion so as to vary increasingly outward and to have an angular rotational component likewise varying increasingly outward from the value 215 in Diagram 17^d to the value 380 in Diagram 17^f.

In Figure 8 appears an assemblage of the blade sections and vector diagrams which correspond to another section of the machine of Figure 5. The vector Diagrams 17^d, 17^e, and 17^f have been reproduced as carried over from Figure 6 and serve to illustrate the characteristic of flow of the fluid discharged from stator element 17 of

the working compressor section of the machine of the present invention. The next successive blade element is shown to have the blade sections comprising root, mean intermediate, and tip sections shown at 26 in Figure 8. The companion stator element for moving blading 26 is provided at 27. The two elements 26 and 27 also are adapted to operate according to a symmetrical flow diagram. In the same manner as was used for the showing of Figure 7, over the vector Diagram 26° may be superimposed the relative entrance velocity EV_{Rel} of Figure 17° and the discharged absolute velocity DV_{Abs} of Figure 27° of the respective mean intermediate blade sections of blades 26 and 27. The resulting diagram will be substantially symmetrical with respect to the axis of the machine, as is indicative of the eventuality of equal pressure rise transpiring in blading 26 and in blading 27. Subsequent to these two successive pressure rises, the working fluid will be discharged from the trailing edge of the discharge portion of blade 27 in the fashion of velocity Diagrams 27^d, 27^e, and 27^f. It will be noted that the absolute velocities in Diagrams 27^d, 27^e, and 27^f vary from the values 420 to 560 while the angular rotational velocities vary from 215 outward to 364, both sets of velocities having an increasing outward characteristic. In Figure 8 the velocity diagrams, intermediate Diagrams 27^d, 27^e, and 27^f and the Diagrams 87^d, 87^e, and 87^f have been omitted, being largely a reproduction of the diagrams given for blades 16, 17, 26, and 27. Actually, as many working compressor stages may be provided as is appropriate for the pressure rise desirable and for the purposes of Figure 5 some eight sets of rotor and stator blading have been shown. The last row in the working compressor portion of the machine in Figure 5 comprises blades 87, the sections of which appear also in Figure 8. As is a fact brought out by the diagrams for velocity 87^d, 87^e, and 87^f of Figure 8, the increasing outward characteristic of absolute velocity and angular rotational velocity is still maintained in the fluid flow upon discharge from the working compressor stator blade 87. At the root thereof the absolute velocity will be seen to be 445, at the mean intermediate section 465, and as accords with velocity Diagram 87^f, 495 at the tip. The respective angular rotational velocities of the radially successive blade sections of velocity Diagrams 87^d, 87^e, and 87^f are respectively 215, 243, and 271.

In Figure 8 the like reference numerals 18, 19, and 20 correspond with the reference numerals of the blading of Figure 5. Between the outlet means 20 in Figure 8 and the last set of blading 87 in the working compressor is interposed the educer comprising rotor element 18 and stator element 19. The tip section of the rotor blade 18 will be observed to have a speed of 780, whereas the mean intermediate section has a blade speed of 740, and the root section a blade speed of 700. When these quantities are added vectorially to the increasing absolute velocities noted in the respective velocity Diagrams 87^d, 87^e, and 87^f, the resulting relative incoming velocity assumes the values varying increasingly outward at 615 in Figure 87^d, 640 in Figure 87^e, and 655 in Figure 87^f. The trailing edges of the educer rotor 18 are proportioned and set for a fluid turning therethrough such as to bring into substantial uniformity the relative discharge velocities. These angles of lift or angles of turn indicated respectively at X_{18} , Y_{18} , and Z_{18} yield respectively

the relative discharge velocities of value 475 in Diagram 18^d, 478 in Diagram 18^e and 482 in Diagram 18^f, a substantially constant value. Moreover, from an examination of Figures 87^d, 87^e, and 87^f in comparison with the respective Figures 18^d, 18^e, and 18^f, it will be revealed that the absolute angular rotational velocities have been in effect increased by blading 18 inversely with radius such that they likewise approach being substantially constant. That is to say, the tangential velocity 215 of Diagram 87^d has been increased during passage through blading 18 by a relatively large amount to yield the value 485 in Diagram 18^d; the angular rotational velocity 271 of Figure 87^f has been changed during passage of the fluid through the tip section of blade 18 by a relatively lesser amount to result in an angular rotational velocity of 475 in Diagram 18^f, which is substantially the same as the angular rotational velocity 485 of Diagram 18^d. Similarly the angular rotational velocity at the intermediate section of the blade will be noted to have been changed to 480 in Diagram 18^e. In the stator blading 19 of the educer, the inlet and discharge portions have been so proportioned and set as to provide an angle of lift causing a decrease, in variance with radius outwardly, of absolute angular rotational velocity. The angular rotational velocity will be observed to have changed at the root section from 485 in Diagram 18^d to 256 in Diagram 19^d; from 480 in Diagram 18^e to 243 in Diagram 19^e, and from 475 in Diagram 18^f to 230 as accords with velocity Diagram 19^f. These changes, owing to the angle of lift of the stator blades, are such as to yield an angular rotational velocity along the trailing edge of blade 19 varying inversely with radius, decreasing from the root outwardly from 256 to 243 and thence to 230. The absolute velocities will be noted in the transition from Diagrams 18^d, 18^e, and 18^f to Diagrams 19^d, 19^e, and 19^f to have been slowed relatively proportionately, that is from 640 to 435, from 625 to 425 at the mean intermediate section, and from 605 to 415 at the tip and yet with the ensuing turn angle in blade 19 providing a residual spin component to flow such that the tangential or angular rotational velocity decreases from the element outward as characterizes vortex flow. Once has this vortex flow been re-established as accords with velocity Diagrams 19^d, 19^e, and 19^f, the compressible fluid in the compressor will be understood to have completed the stages of transition following its passage from the original inlet grid.

The blades 20 in Figure 8, which comprise the outlet means, serve in a reverse function to that of the blades of the initial inlet means. The discharge portions of the stator outlet 20 are formed with trailing edges which conform to and effect a fluid discharge substantially free from rotation. The inlet portions of blade 20 are formed so as to present a leading edge of substantially zero angle of attack to the oncoming compressible fluid discharged from the educer and the lift angle selected for the blade then is that angle necessary to remove the residual rotation or spin from the compressible fluid and establish once again an axial flow in a state of equilibrium. It is to be appreciated of course, that during the progress through the compressor the compressible gas has undergone such pressure rise as may be desirable and commensurate with the number of stages for which the compressor is designed. Both the inducer and educer have been shown each as comprising only a single set of rotary and stationary blades, but it is to be understood

that each may comprise more than one set if desired.

The foregoing machine has been described as a compressor but it may also be a turbine within the spirit of the present invention. Compressible fluid or gas with relatively high energy content is so carried as to flow through the machine transferring energy to the machine by causing the rotor to rotate in this latter regard. The changes in the flow through the machine acting as a turbine will be similar to those described for flow through the machine acting as a compressor except that energy of the motive fluid at the end will be less rather than more than at the start and energy will be abstracted rather than added while the energy is variable along the lengths of the blades of the stages.

The invention has been described by means of preferred embodiment illustration but it is not intended to limit the present invention from the inclusion of other equivalent variations and changes in construction such as will be apparent to those skilled in the art.

What is claimed is:

1. A rotary axial-flow fluid power conversion machine having a longitudinal axis, and comprising: a stator element having blades provided with inlet and discharge portions, the inlet portions of the blades being parallel with the axis of the machine and the surfaces of the blades being so curved that the discharge portions thereof are disposed to the axis of the machine at an angle such that the angular rotational velocity of the motive fluid discharged therefrom varies inversely with the distance of the discharge portion surfaces from the axis of the machine; inducer means in series with the stator element and including rotor and stator elements having blades provided with curved surfaces and having inlet and discharge portions, the blades being so curved that discharge portions of the inducer rotor blades are proportioned and set to produce a variation in the inlet and discharge angles of the motive fluid with respect to relative distance of the discharge portion surfaces from the axis of the machine such that the absolute angular rotational velocity of all said fluid discharged from the inducer rotor blade discharge portions is in substantial equality therealong, the discharge portions of the inducer stator blades being proportioned and set to produce a variation in the inlet and discharge angles with respect to the distance of the discharge portion surfaces to the axis of the machine such that the absolute angular rotational velocity of the discharged fluid varies with the distance of the discharge portion surfaces of the inducer stator blades from the axis of the machine, working compressor means in series with the inducer means including rotor and stator elements having blades provided with curved surfaces and having inlet and discharge portions, the last element in the series of working compressor elements being a stator element having the surfaces of the blades thereof so curved that the discharge portions of the blades are disposed to the axis of the machine at an angle such that the relative and angular rotational velocities of the discharged fluid vary with the distance of the discharge portion surfaces from the axis of the machine; educer means in series with the working compressor means and including rotor and stator elements having blades with curved surfaces and being provided with inlet and discharge portions, the discharge portions of the rotor blades being proportioned and set for turning and slowing the

final discharge from the working compressor means to bring the absolute angular rotational velocity of all said fluid discharged from the rotor blades into substantial equality therealong, with the surfaces of the educer stator blades being so curved that the discharge portions thereof are disposed at an angle to the axis of the machine such that the absolute angular rotational velocity of the motive fluid discharged therefrom varies inversely with the distance of the discharge portion surfaces from the axis of the machine; and outlet means in series with the educer means and including a stator element having blades with curved surfaces and being provided with inlet and discharge portions, the blades of the stator element being so curved that the discharge portions thereof are disposed parallel to the axis of the machine such as to conform to and effect a fluid discharge substantially free from rotation.

2. A rotary axial-flow fluid power conversion machine having a longitudinal axis, and comprising: a stator element having blades provided with inlet and discharge portions, the inlet portions of the blades being parallel with the axis of the machine and the surfaces of the blades being so curved that the discharge portions thereof are disposed to the axis of the machine at an angle such that the angular rotational velocity of the motive fluid discharged therefrom varies inversely with the distance of the discharge portion surfaces from the axis of the machine; inducer means in series with the stator element and including rotor and stator elements having blades provided with curved surfaces and having inlet and discharge portions, the blades being so curved that discharge portions of the inducer rotor blades are proportioned and set to produce a variation in the inlet and discharge angles of the motive fluid with respect to relative distance of the discharge portion surfaces from the axis of the machine such that the absolute angular rotational velocity of all said fluid discharged from the inducer rotor blade discharge portions is in substantial equality therealong, the discharge portions of the inducer stator blades being proportioned and set to produce a variation in the inlet and discharge angles with respect to the distance of the discharge portion surfaces to the axis of the machine such that the absolute angular rotational velocity of the discharged fluid varies with the distance of the discharge portion surfaces of the inducer stator blades from the axis of the machine, working compressor means in series with the inducer means including rotor and stator elements having blades provided with curved surfaces and having inlet and discharge portions, the rotor and stator elements being operatively arranged respectively in series with the inducer means and the discharge portions of the respective blades thereof being proportioned and set for a variation in the inlet and discharge angles at the mean distance of the discharge portion surfaces from the axis of the machine such that the change of inlet to discharge fluid velocities relative to working compressor rotor element in respect of the axis of the machine is substantially the equivalent of and opposite to the change of inlet to discharge fluid velocities relative to the succeeding working compressor stator element in respect of the axis of the machine, the last element in the series of working compressor elements being a stator element having the surfaces of the blades thereof so curved that the discharge portions of the blades are disposed to the axis of the machine at an angle such that the relative and

angular rotational velocities of the discharged fluid vary with the distance of the discharge portion surfaces from the axis of the machine; educer means in series with the working compressor means and including rotor and stator elements having blades with curved surfaces and being provided with inlet and discharge portions, the discharge portions of the rotor blades being proportioned and set for turning and slowing the final discharge from the working compressor means to bring the absolute angular rotational velocity of all said fluid discharged from the rotor blades into substantial equality therealong, with the surfaces of the educer stator blades being so curved that the discharge portions thereof are disposed at an angle to the axis of the machine such that the absolute angular rotational velocity of the motive fluid discharged therefrom varies inversely with the distance of the discharge portion surfaces from the axis of the machine; and outlet means in series with the educer means and including a stator element having blades with curved surfaces and being provided with inlet and discharge portions, the blades of the stator element being so curved that the discharge portions thereof are disposed parallel to the axis of the machine such as to conform to and effect a fluid discharge substantially free from rotation.

3. In an axial flow compressor characterized by a working compressor portion comprising sets of fixed blades, and rotor and stator parts in series with one another including a discharging stator part which constitutes the last said part in series and which carries one set of the fixed blades aforesaid, said one set of fixed blades being provided with curved surfaces and having inlet and discharge portions, said discharging stator part having said one set of fixed blades so curved that the discharge portions of the blades are disposed to the axis of the compressor at an angle such that the relative and angular discharge rotational velocities of the fluid discharged from the discharge portions of the discharging stator part vary with the distance of the discharge portion surfaces from the axis of the machine: educing and final discharge means in series with the working compressor means and including blades with curved surfaces provided with inlet and discharge portions, and a plurality of elements carrying the blades fixed thereto, one of said elements constituting a rotor arranged adjacent said discharging stator part with the discharge portions of the rotor blades proportioned and set with respect to the axis of the compressor for turning and slowing the final discharge from the working compressor means to bring the absolute angular rotational velocity of all said fluid discharge from the rotor blades into substantial equality along the discharge portions of the latter, the remainder of said elements comprising a stator unit in series with the rotor aforesaid and having the blades thereof selected and set for slowing and turning the flow of the fluid in effectively removing the residual rotation from the final discharge and establishing axial flow in state of equilibrium, the final discharge portions of the just named blades having the surfaces thereof so curved as to be disposed parallel to the axis of the compressor such as to conform to and effect the final fluid discharge in the foregoing described manner substantially free from rotation.

4. In an axial flow compressor characterized by a working compressor portion comprising

sets of fixed blades, and rotor and stator parts in series with one another including a discharging stator part which constitutes the last said part in series and which carries one set of the fixed blades aforesaid, said one set of fixed blades being provided with curved surfaces and having inlet and discharge portions, said discharging stator part having said one set of fixed blades so curved that the discharge portions of the blades are disposed to the axis of the compressor at an angle such that the relative and angular discharge rotational velocities of the fluid discharge from the discharge portions of the discharging stator part vary with the distance of the discharge portion surfaces from the axis of the machine: educer means in series with the working compressor means and including rotor and stator elements having blades with curved surfaces and being provided with inlet and discharge portions, the discharge portions of the rotor blades being proportioned and set for turning and slowing the final discharge from the working compressor means to bring the absolute angular rotational velocity of all said fluid discharged from the rotor blades into substantial equality therealong, with the surfaces of the educer stator blades being so curved that the discharge portions thereof are disposed at an angle to the axis of the compressor such that the absolute angular rotational velocity of the motive fluid discharged therefrom varies inversely with the distance of the discharge portion surfaces from the axis of the compressor; and outlet means in series with the educer means and including a stator element having blades with curved surfaces and being provided with inlet and discharge portions, the blades of the stator element being so curved that the discharge portions thereof are disposed parallel to the axis of the compressor such as to conform to and effect a fluid discharge substantially free from rotation.

5. A rotary axial-flow compressor having a longitudinal axis, and comprising: a stator element having blades provided with inlet and discharge portions, the inlet portions of the blades being parallel with the axis of the compressor and the surfaces of the blades being so curved that the discharge portions thereof are disposed to the axis of the machine at an angle such that the angular rotational velocity of the motive fluid discharged therefrom varies inversely with the distance of the discharge portion surfaces from the axis of the compressor; inducer means in series with the stator element and including rotor and stator elements having blades provided with curved surfaces and having inlet and dis-

charge portions, the blades being so curved that discharge portions of the inducer rotor blades are proportioned and set to produce a variation in the inlet and discharge angles of the motive fluid with respect to relative distance of the discharge portion surfaces from the axis of the compressor such that the absolute angular rotational velocity of all said fluid discharged from the inducer rotor blade discharge portions is in substantial equality therealong, the discharge portions of the inducer stator blades being proportioned and set to produce a variation in the inlet and discharge angles with respect to the distance of the discharge portion surfaces to the axis of the compressor such that the absolute angular rotational velocity of the discharged fluid varies with the distance of the discharge portion surfaces of the inducer stator blades from the axis of the compressor; and working compressor means in series with the inducer means including rotor and stator elements having blades provided with curved surfaces and having inlet and discharge portions, the rotor and stator elements being operatively arranged respectively in series with the inducer means and the discharge portions of the respective blades thereof being proportioned and set for a variation in the inlet and discharge angles at the mean distance of the discharge portion surfaces from the axis of the compressor such that the change of inlet to discharge fluid velocities relative to working compressor rotor element in respect of the axis of the compressor is substantially the equivalent of and opposite to the change of inlet to discharge fluid velocities relative to the succeeding working compressor stator element in respect of the axis of the machine, the last element in the series of working compressor elements being a stator element having the surfaces of the blades thereof so curved that the discharge portions of the blades are disposed to the axis of the compressor at an angle such that the relative and angular rotational velocities of the discharged fluid vary with the distance of the discharge portion surfaces from the axis of the compressor.
